(57) **CLAIM**

The ornamental design for a container for food or the like, as shown and described.

DESCRIPTION

FIG. 1 is a perspective view of a container for food or the like of the present invention;

FIG. 2 is a front elevation view of a container illustrated in FIG. 1;

FIG. 3 is a side view of a container illustrated in FIG. 1;

FIG. 4 is a top view of a container illustrated in FIG. 1; and,

FIG. 5 is a bottom view of a container illustrated in FIG. 1.

It is understood that the broken lines within the claimed design indicate perforation lines, which form part of the claim.
